UNITED STATES PATENT OFFICE.

FRANK E. CASE, OF SCHENECTADY, NEW YORK, ASSIGNOR TO GENERAL ELECTRIC COMPANY, A CORPORATION OF NEW YORK.

TERMINAL FOR ELECTRIC CONDUCTORS.

1,019,423.

Specification of Letters Patent. Patented Mar. 5, 1912.

Application filed March 7, 1906. Serial No. 304,648.

To all whom it may concern:

Be it known that I, FRANK E. CASE, a citizen of the United States, residing at Schenectady, in the county of Schenectady and 5 State of New York, have invented certain new and useful Improvements in Terminals for Electric Conductors, of which the following is a specification.

This invention relates to connecting terminals for electrical conductors and has for 10 its object the provision of a device of this character which is very inexpensive to manufacture, while at the same time being very reliable and convenient.

One of the objects of my invention is to 15 produce a terminal from a metallic strip which may be punched out of or cut from sheet metal and which may be given the desired form under a punch press with the 20 use of very little or no hand work.

In carrying out my invention I punch a 25 blank out of sheet metal which is provided at its opposite ends with wings which are adapted to be bent so as to form holding 30 clips for the conductor. The strip is then bent intermediate its ends so as to bring the two clips adjacent.

In the drawings, in which I have shown a 35 preferred embodiment of my invention, Figure 1 is a plan view of a punched blank from which my connecting terminal is formed; Fig. 2 is a perspective view of the terminal completely formed; and Fig. 3 is a view of 40 conductors and secured to an insulating base.

Referring to the drawings, 10 is a metallic strip of some good conducting material, such as copper or brass. This strip is preferably formed by being punched out of sheet 45 metal and is provided with wings 11 and 12 which are so proportioned as to form clips 11' and 12' of the desired dimension. I have shown these clips of different sizes, the large one 11' being of a size sufficient to 50 substantially encircle the insulation of the conductor, while the clip 12' encircles the conductor itself, thus making a very firm support for the conductor and at the same time a thoroughly efficient electrical connection. The strip is also preferably perforated at 13 and 14. The strip is then bent

upon itself intermediate the perforations, as on the line 15, so as to bring the wings longitudinally adjacent each other, the wings preferably being first formed into the 55 clips. If the perforations are made in the strip before it is bent on itself the line of bending should be such that the perforations will come fair with each other. Where the clips 11' and 12' are to be of different 60 sizes it is of course desirable that they be co-axial, or concentric, where, as in the present case, they are circular. This is done, as shown in Figs. 2 and 3, by bending the metal adjacent the clip 12', as at 16, so as to give 65 the clip an offset to make them concentric. The clips may be formed in the punch press or in any desired manner, and the bending of the strip on to itself may be similarly performed. The perforations 13 and 14 will 70 form a securing and fastening means for the terminal, although, of course, other means may be provided without departing from the spirit of my invention. These clips may 75 be used in pairs and secured by means of the bolt 17 and nuts 18, as shown in Fig. 3.

It will thus be seen that I have provided a very simple and efficient terminal which, in addition to forming a firm and reliable support for the conductors, makes also a 80 very efficient contact. The insulation is firmly held in place and the raveling of the insulation is prevented.

It should be understood, of course, that 85 various modifications of my device will suggest themselves to those skilled in the art, all of which will come within the spirit of my invention in so far as they fall within the scope of the claims annexed to and forming a part of this specification.

What I claim as new and desire to secure by Letters Patent of the United States, is,

1. A terminal for electric conductors comprising a metallic strip having holding clips formed at opposite ends thereof, said clips 95 being arranged so as to be co-axial and engage adjacent portions of the conductor.

2. A terminal for electric conductors comprising a metallic strip having integral clips formed at opposite ends, said clips being arranged so as to be co-axial and engage adjacent portions of the conductor. 100

3. A terminal for electric conductors comprising a duplex metallic strip having clips formed at one end thereof, said clips being co-axial and longitudinally adjacent, one clip being arranged to surround the conductor and the other to surround the insulator.

In witness whereof, I have hereunto set my hand this 6th day of March, 1906.

FRANK E. CASE.
